UNITED STATES PATENT OFFICE.

CHARLES G. STOWELL AND ROBERT F. SIMME, OF DULUTH, MINNESOTA.

WAX ELIMINATOR.

Application filed October 29, 1921. Serial No. 511,510.

To all whom it may concern:

Be it known that we, CHARLES G. STOWELL and ROBERT F. SIMME, citizens of the United States, residing at Duluth, in the county of 5 St. Louis and State of Minnesota, have invented certain new and useful Improvements in Wax Eliminators, of which we do declare the following to be a specification.

Our invention relates to wax eliminator, 10 and has for its object the provision of a simple, cheap, durable, and convenient eliminator for eliminating the wax and excess moisture from dentists' investment moulds.

It consists of the structures, combinations 15 and arrangements of parts hereinafter described and claimed.

In the drawings, Fig. 1, is a side elevation of our said invention. Fig. 2, is a central vertical section of the same. Fig. 3, is a top 20 plan view of said invention. And Fig. 4, is a horizontal section of the same on the line A—B of Fig. 2.

In the drawings, 1, is a gas burner of any suitable structure, preferably comprising a 25 gas and air containing and mixing chamber 1^a, provided with a gas intake port 1^b, and an air intake port or ports 1^c, which air intake ports are preferably governed by an adjustable gate 1^d. At, or near the upper 30 end of said burner is a horizontally disposed cover or diaphragm 1^e, the upper surface of which is preferably concave. One of the features of our said invention is that we 35 form an aperture in said diaphragm, as at 1^f, and position below it a drain or discharge pipe 2, of any suitable form or structure, communicating at one end with said aperture and extending at the opposite end out of said chamber. If desired, a bucket 3 may 40 be suspended from, or positioned below the outer end of said drain to catch the wax and water discharged therefrom. Upon said diaphragm, concentric with said aperture, is positioned a cylinder or retort 4, open at 45 each end and preferably removable from said diaphragm.

Communicating with said chamber and with the area above said diaphragm outside of said retort, are one or more gas ports, 50 1^g, preferably arranged in a circle around said retort and adapted to discharge toward the same. Said ports 1^g preferably extend through said diaphragm. A flexible tube 5,

is preferably provided for connecting the intake port of said burner to a source of gas 55 supply (not shown).

Heretofore, it was customary to provide for this purpose a retort having an individual closed bottom; or else an open-bottom retort adapted to discharge into an underlying closed-bottom receiving cup within the 60 burner, from which the water and wax could not escape out of the burner and in which the wax tended to burn or gum, or from which the mixture tended to spatter 65 or boil over on to adjacent parts within the burner; which forms of closed retort, or of inclosed drain cup required considerable time and labor for cleaning.

Also the eliminated wax in the closed retort or flask tended to adhere in appreciable quantities to any portion of the mould which contacted with the bottom of the retort, and to drip therefrom if the mould was withdrawn while hot, or to cling thereto if 75 the mould was withdrawn after cooling.

In the operation of our invention, the investment mould, including plaster and wax—the plaster usually containing considerable excess moisture—is placed in the retort and the gas jets at the ports 1^g are 80 lighted. The flames of said jets, extending toward said retort, heat the same and the contained mould to a high temperature, whereby the moisture is drawn, driven, or 85 boiled from said plaster and evaporated, or drawn off through said drain. At the same time the wax is melted from said mould and immediately run off through said drain and is collected in said bucket and saved. The 90 burner is thus kept clean. We are aware that somewhat similar burners have heretofore been constructed, but without a drain or pipe communicating with the retort and discharging out of the burner; nor provided 95 with a cover or diaphragm as herein described.

It is obvious that the structure embodying our invention may be changed or modified in certain particulars within the scope and 100 spirit of our claim.

What we claim is—

In a wax eliminator, the combination of a burner comprising a mixing chamber provided with an intake port, a cover or 105 diaphragm extending over said mixing

2
chamber, an open bottom retort erected upon said diaphragm, said diaphragm having gas discharge ports formed therein adapted to discharge against the outer side of said retort, said diaphragm having an aperture formed therethrough beneath the open bottom of said retort, and a discharge pipe communicating with said aperture at the lower side of said diaphragm and extending down-

wardly through one of the walls of said mixing chamber.

In testimony whereof, we hereunto affix our signatures, in presence of two witnesses.

CHARLES G. STOWELL.
ROBERT F. SIMME.
